UNITED STATES PATENT OFFICE.

JAMES MICHAEL CAMMACK, OF SUMMIT, NEW JERSEY.

INSTRUMENT FOR REMOVING FLOOR-BOARDS SINGLY.

SPECIFICATION forming part of Letters Patent No. 700,169, dated May 20, 1902.

Application filed January 21, 1901. Serial No. 44,054. (No model.)

To all whom it may concern:

Be it known that I, JAMES MICHAEL CAMMACK, a citizen of the United States, residing at Summit, county of Union, State of New Jersey, have invented a new and useful Instrument for Removing Floor-Boards Singly, of which the following is a specification.

My invention relates to means for removing one board at a time from a floor or ceiling or other place where boards have been laid in bank or series, tongued-and-grooved together, and nailed to secure them in place and to do so without injuring the boards contiguous thereto. At the present time in removing 15 flooring made of tongued-and-grooved or matched board for any purpose whatever it is necessary to destroy or mutilate several boards.

To this end my invention consists in an instrument fully specified herein and claimed at the end of this specification.

In order that those skilled in the art to which my invention appertains may understand, construct, and use my invention, I will 25 proceed to describe it, referring to the drawings herewith, in which—

Figure 1 is an elevation of my invention, and Fig. 2 is a vertical central part section thereof in side view. A is the handle and 30 holder, usually of wood. B is a thin sheet-metal blade, usually of steel, set in the holder. b represents screws to hold the blade B in place in holder A. C is a metal key or resistance-plate to receive and take up the 35 shock of blows given in use.

Fig. 3 is a cross-section of a tongued-and-grooved flooring, showing the instrument in use. E represents the boards. F represents the tongues matched into the grooves G. H 40 represents the nails used to secure the boards E to the beams or underflooring J, as the case may be.

In removing one board from its neighbors the blade B is driven between the two contiguous boards, and so cuts the tongue away 45

successively from one end of the board to the other by repeated insertions and blows upon the holder A. The resistance-plate C receiving the shock prevents the metal blade B from splitting the holder A. The blade B is 50 inserted between the two contiguous boards at a slight angle vertically, and after cutting away the tongue F and part of the bottom of the board by a depression of the holder the board from which the tongue has been cut away and 55 released from its neighbor is free to be raised and is raised and the said board is easily removed. This operation is quickly effected and much time is saved thereby over the old method and the board can be replaced with- 60 out in any way impairing the firmness or appearance of the floor. Plumbers and gas fitters and electric-light men are frequently called upon to use such an instrument, and my invention fills a long-felt want. 65

At the base of the holder A on each side of the blade B, I place a piece of soft material D to prevent injury to the floor in case the holder accidentally comes in contact therewith with the force of the blow in operation. 70

Having now fully described my invention and the manner in which I have embodied it, what I claim as new and as my invention, and desire to secure by Letters Patent, is—

An instrument for removing floor-boards 75 singly, consisting of and comprising, a wooden handle; A, having comparatively thin blade B; and a transverse resistance-plate C, wide enough to resist the thrust of said blade, and the lower end of said handle having baffle- 80 cushions D, substantially as, and for the purposes specified.

In testimony whereof I have signed my name to this specification, in the presence of two subscribing witnesses, this 24th day of 85 December, 1900.

JAMES MICHAEL CAMMACK.
